UNITED STATES PATENT OFFICE.

ARTHUR MENG, OF CLEVELAND, OHIO.

DESIGN FOR A RING-DISPLAY HOLDER.

Application filed August 3, 1922. Serial No. 3,274. Term of patent 7 years.

To all whom it may concern:

Be it known that I, ARTHUR MENG, a citizen of Germany, residing at Cleveland, in the county of Cuyahoga and State of Ohio, have invented a new, original, and ornamental design for a Ring-Display Holder, of which the following is a specification, reference being had to the accompanying drawing, forming part thereof.

The figure in the drawing is a front elevation of a ring display holder, showing my new design.

I claim:

The ornamental design for a ring display holder, as shown.

ARTHUR MENG.
